UNITED STATES PATENT OFFICE.

PATRICK ROWE AND JAMES J. SCANLIN, OF LOWELL, MASSACHUSETTS.

TRUNK FOR COTTON-OPENERS.

SPECIFICATION forming part of Letters Patent No. 254,385, dated February 28, 1882.

Application filed August 16, 1881. (No model.)

To all whom it may concern:

Be it known that we, PATRICK ROWE and JAMES J. SCANLIN, of Lowell, in the county of Middlesex and State of Massachusetts, have 5 invented a new and Improved Trunk for Cotton-Openers, of which the following is a full, clear, and exact specification.

The object of our invention is to facilitate 10 cleaning the trunks in which the dust and sand are collected that drops from the cotton as it passes from the opening-machine to the picker.

The invention consists in the combination, 15 with a cotton-opener trunk provided with pivoted floor-sections, of a car adapted to pass under the floor-sections of the trunk, and provided with means for tilting the sections thereof and dumping the refuse from the bottom into the car; also, in the combination, with the cotton-opener trunk, of the pivoted sections, the projections, 20 the cam, and the car; also, in the combination, with the cotton-opener trunk, of the pivoted sections, the projections, having weights attached thereto, the cam, and the car; also, in the combination, with the cotton-opener 25 trunk, of the pivoted sections, the projections, the cam, and means for adjusting the same, and the car; also, in the combination, with the cotton-opener trunk, of the pivoted sections, the projections, the cam, the cross-bar, the binding-screw, and the car; and also in the combination, 30 with the cotton-opener trunk, of the pivoted sections, the projections, the cam, the cross-bar, the racks, the cog-wheels, the studded wheel, and the chain, all as hereinafter described.

In the accompanying drawings, Figure 1 is 35 a longitudinal elevation of our improved trunk for cotton-openers, parts being shown in section. Fig. 2 is a cross-sectional elevation of the same. Fig. 3 is a plan view of the car.

Similar letters of reference indicate corresponding parts.

The trunk A of a cotton-opening machine is 40 provided with a grating, B, over which the cotton passes from the cotton-opener to the picker, as indicated by the arrow a'. The bottom of the trunk A is composed of a series of pivoted boards or sections, C' C² C³, &c., provided on the under side with projections D' D², &c., having a weight, E' E², &c., attached thereto, 45 which keeps the sections C' C², &c., in a hori-

zontal position—that is, the openings in the bottom of the trunk A are closed. These projections D' D², &c., are not in one straight longitudinal line, but each one is located a different distance from the ends of the sections C' C², &c., as shown in Fig. 2. A car, F, runs on tracks or rails G below the trunk. A cam, H, provided on its outer end with a number of teeth, slides on a bar, J, attached to two cogged 55 end bars or racks, K, engaging with the cog-wheels L on the ends of a shaft, M, of the car F. By means of a binding-screw, N, the cam H can be locked in any desired position on the bar J, which is provided with subdivisions, 60 (marked 1, 2, and 3,) and corresponding in position with the projections D', D², and D³.

A circumferentially studded wheel, O, is mounted on one end of the shaft M, and a chain, P, passing over this wheel, passes down to the 65 floor of the room in which the trunk A is located. The car F is propelled or drawn by means of a cord or equivalent, Q, which is wound on a roller, R. The trunk may be provided with any number of pivoted sections C' 70 C², &c., in its bottom.

The operation is as follows: From the cotton passing through the trunk A the sand and dust fall through the grating B upon the sections C' C², &c., and accumulate there. If the sections C' are to be tilted, the cam H is adjusted 75 on the subdivision 1 on the bar J, and the car is drawn in the direction of the arrow a', causing the cam H to strike the projection D', thereby causing the sections C' to tilt, as shown in Fig. 1, the sand and dust sliding down these tilted sections into the car F. In order to prevent the dust and sand from accumulating in one end of the car, the cam must be adjusted in 80 different positions in relation to the front and rear of the car. This is accomplished by means of the chain P, for by means of the same the wheels O and L can be slightly rotated, whereby the racks K, the bar J, and the cam H will be moved forward or backward more or less, 85 and consequently the lowered end of the pivoted section of the trunk-bottom will be more or less from the rear end of the car. As the cam H is toothed, it will vibrate the projections D' D², &c., and the sections C' C², &c., slightly, 90 thereby causing the sand and dust to slide off more rapidly.

Having thus fully described our invention, we claim as new and desire to secure by Letters Patent—

- 5 1. The combination, substantially as herein shown and described, with a cotton-opener trunk provided with pivoted floor-sections, of a car adapted to pass under the floor-sections of the trunk, and provided with means for tilting the sections thereof and dumping the refuse 10 from the bottom into the car, as set forth.
- 10 2. The combination, with the cotton-opener trunk A, of the pivoted sections C' C², &c., the projections D' D², the cam H, and the car F, substantially as herein shown and described, 15 and for the purpose set forth.
- 15 3. The combination, with the cotton-opener trunk A, of the pivoted sections C' C², the projections D' D², having the weights E' E² attached thereto, the cam H, and the car F, substantially as herein shown and described, and 20 for the purpose set forth.
- 20 4. The combination, with the cotton-opener

trunk A, of the pivoted sections C' C², the projections D' D², the cam H, and means for adjusting the same, and the car F, substantially 25 as herein shown and described, and for the purpose set forth.

5. The combination, with the cotton-opener trunk A, of the pivoted sections C' C², the projections D' D², the cam H, the bar J, the binding-screw N, and the car F, substantially as 30 herein shown and described, and for the purpose set forth.

6. The combination, with the cotton-opener trunk A, of the pivoted sections C' C², the projections D' D², the cam H, the bar J, the racks K, the cog-wheels L, the studded wheel O, and the chain P, substantially as herein shown and 35 described, and for the purpose set forth.
